UNITED STATES PATENT OFFICE.

AUGUSTO BISSIRI, OF LOS ANGELES, CALIFORNIA, ASSIGNOR TO GENERAL ELECTRIC COMPANY, A CORPORATION OF NEW YORK.

TRANSMISSION OF PICTURES.

Application filed January 4, 1928. Serial No. 244,531.

My invention relates to the transmission of pictures or the like, and has for its principal object the provision of an improved apparatus and method of operation whereby pictures may be readily transmitted from one point to another.

In the past, various picture transmitting apparatus comprising either a radio transmitter and receiver or a transmitter and receiver interconnected by electrical conductors have been provided. Many of these apparatus involve the use of both means for producing a light dependent on the shade of the picture to be transmitted and means for converting such light into electrical impulses which must be reconverted to light at the receiving station. Such apparatus is not altogether satisfactory because it is more or less complicated in structure and involves variable illumination and visibility of the screen on which the picture is reproduced. In accordance with my invention, these difficulties are largely avoided or altogether obviated by the provision of a continuously illuminated screen which is arranged to have its contour and shading varied in accordance with the shading of the picture.

My invention will be better understood from the following description when considered in connection with the accompanying drawings and its scope will be pointed out in the appended claims.

Referring to the drawings, Fig. 1 shows a picture producing apparatus wherein my invention has been embodied; and Figs. 2 to 6 illustrate various details in the construction of this receiving apparatus.

This apparatus comprises a screen 1 which is arranged to be continuously illuminated by suitable light sources 2 and 3, and is provided with a plurality of movable elements controlled by commutators or contact making devices 4 and 5 connected to a radio receiver through cables 7 and 8. The commutators 4 and 5 are mechanically coupled together through gears 9 to 12 for the purpose of maintaining a definite relation between their speeds of rotation and are arranged to be driven by a motor 13 which is coupled to the gear 11 and is operated in synchronism with a picture transmitting apparatus (not shown). Each of the squares in the screen 1 represents one of a plurality of elemental surfaces which are controlled by the commutators 4 and 5 and may be moved in a direc-

tion perpendicular to the screen surface for the purpose of varying the amount of light reflected from them. The actual construction of the screen 1 will be readily understood upon consideration of Figs. 2 to 6.

As indicated by these figures, each elemental portion 14 of the screen may be made in the form of a pyramid, a cone or the like, supported on pivoted members 15 and arranged to be moved transversely to the surface of the screen by means of electroresponsive devices 16 which are energized in accordance with the current transmitted to them through the radio receiver 6, the cables 7 and 8, the commutators 4 and 5 and the cables 17 and 18. This current varies in accordance with the shading of the picture to be produced, and it will be readily understood that, when the picture transmitting and receiving apparatus are properly synchronized, the magnitude of the currents supplied to the electroresponsive devices 16 controlling the various elemental portions 14 of the receiving screen 1 will be dependent on the shading of the corresponding elemental portions of the picture or image to be transmitted. Under these conditions, the position of each elemental portion 14 of the screen, and the amount of light which each of these portions receives from the sources 2 and 3 and reflects is dependent on the shading of a corresponding elemental portion of the picture or image.

The rapidity with which the electrical connections are changed from one to another of the electroresponsive devices 16 is dependent on the rotational speed of the driving motor 13 and ordinarily need not be faster than that required to complete the connections of all the electroresponsive devices more than once every one sixteenth of a second. Thus assuming for example that the screen 1 is square and contains one hundred elemental surface portions, the commutator 5 should be driven at a speed of 160 revolutions per second and the commutator 4 should be driven at a speed of 1600 revolutions per second.

The manner in which the reflected light is determined by the positions of the elemental portions 14 of the screen 1 is indicated more clearly by Fig. 3 wherein four different positions of these elements are indicated. It will be observed that the maximum amount of light is reflected by the upper elemental sur-

face, that less light is reflected by the next lower elemental surface, that still less light is reflected by the next lower elemental surface, and that the lowest elemental surface is substantially black. It should be clearly understood that all parts of the screen except the elemental surfaces are black, that these surfaces are white, and that the screen is continuously illuminated in a plane parallel with its surface. Under these conditions, the illumination and visibility of the screen are continuous and the shading of the reproduced picture is altogether dependent on the positions of the various elemental surfaces.

15 It will be readily understood by those skilled in the art that continuous illumination of the screen has the advantages that the intensity of the illumination is unlimited, the variability in the source of light is eliminated, economy in the light apparatus is produced and the screen is made independent of the source of light; and that continuous visibility is advantageous in that each elemental surface has the same permanent visibility regardless of the number of light sources, a change in the position of the elemental surfaces of the screen occurs only where the shading of the picture to be transmitted has a predetermined value, and the speed at which 20 the screen is scanned may be reduced to one eighth of a second without producing objectionable flickering. It will be apparent that any suitable means other than those shown and described may be utilized for varying in accordance with the picture to be produced.

25 The embodiment of the invention illustrated and described herein has been selected

for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

40 45 What I claim as new and desire to secure by Letters Patent of the United States is:

1. A picture producing apparatus comprising a screen provided with a plurality of pyramidal surfaces arranged to have their 50 positions determined by the shading of the picture to be produced.

2. A picture producing apparatus comprising a screen provided with movable pyramidal surfaces, means for illuminating said 55 screen, and means for causing said surfaces to assume positions dependent on the shading of the picture to be produced on said screen.

3. A picture producing apparatus comprising a screen provided with a plurality of 60 pyramidal surfaces arranged to be moved independently of one another, and means for continuously illuminating said screen.

4. A picture producing apparatus comprising a screen provided with a plurality of 65 pyramidal surfaces movable independently of one another, means for continuously illuminating said screen, and means for causing said surfaces to assume positions dependent on the shading of the picture.

70 In witness whereof, I have hereunto set my hand, this 29 day of December, 1927.

AUGUSTO BISSIRI.
